[57] CLAIM

The ornamental design for a cosmetic dispenser, as shown and described.

DESCRIPTION

FIG. 1 is a top, front and right side perspective view of a cosmetic dispenser showing our new design;

FIG. 2 is a side elevational view thereof, the opposite side being the same;

FIG. 3 is a top plan view thereof;

FIG. 4 is a front elevational view thereof;

FIG. 5 is a rear elevational view thereof; and,

FIG. 6 is a bottom plan view thereof, the broken lines being for illustrative purposes and forming no part of the claimed design.
